UNITED STATES PATENT OFFICE

2,648,211

SQUEEZER EXTRACTOR WASHING MACHINE

Friedrich Eberlein, Stuttgart-Riedenberg, Germany, assignor to Henkel & Cie, G. m. b. H., Dusseldorf-Holthausen, Germany, a limited liability company of Germany

Application June 14, 1950, Serial No. 167,974
In Germany June 17, 1949

1 Claim. (Cl. 68—21)

1

This invention relates to washing machines. Heretofore, the steps of moving the wash in the washing liquid and the removal of such liquid, were carried out by separate devices such as washing machines, wringers, centrifuges and presses.

An object of the present invention is the provision of a simple and effectively operating device wherein the movement of the wash in the washing liquid and the removal of the latter are carried out directly one after the other in the same device, and without being broken up into separate steps.

Other objects of the present invention will become apparent in the course of the following specification.

The objects of the present invention may be realized through the provision of a washing machine having a rotary drum which contains the wash and which is provided with one or two end walls movable axially for the purpose of compressing the wash.

The invention will appear more clearly from the following detailed description when taken in connection with the accompanying drawings showing, by way of example, a preferred embodiment of the inventive idea.

In the drawings:

Figure 1 illustrates diagrammatically, in longitudinal section, a washing machine constructed in accordance with the principles of the present invention;

Figure 2 is a transverse section along the line 2—2 of Figure 1.

The washing machine shown diagrammatically in the drawings includes a cylindrical container 10 which is mounted on the legs 11. In connection with the container 10, there are special openings or devices to let water into the container, to add washing-powder to the water, to heat the washing fluid and to remove it from the container. As these openings and devices are not a subject of this invention, these openings and devices are not shown in the drawings. A drum 12 is located within the casing 10. The drum 12 has end members 3 which are rotatably connected with the end walls 13 of the casing 10 by means of flanged pipe ends 14 which are connected to the end members 3 and which extend through tubular supports 15 provided in the end walls 13 of the casing 10.

The end members 3 of the drum 12 are of smaller diameter than the central section 16 of the drum. The cylindric wall of this central section 16 is perforated.

The section 16 of the drum contains end parti-

2

tions 4 which are movable within the drum in the direction of its longitudinal axis.

The inner surface of the central portion 16 of the drum 12 is provided with guide rails 8, the outline of which is indicated in Figure 2. The end partitions 4 have recesses 17 corresponding to the outline of the guides 8 so that the end partitions 4 are mounted upon the guides 8. It is apparent that the guides 8 extend into the interior of the drum and are used for moving the wash.

Stretchable bodies 5, which are made of stretchable material, such as rubber, extend between the end members 3, immovable in direction of their longitudinal axis, and the longitudinally movable end partitions 4, and are attached to these partitions, so that a hollow space 20 is formed by the stretchable bodies 5 and the members 3 and partitions 4. The tube ends 14 communicate with the hollow spaces 20 and are rotatably connected with pipes 6 for the flow of a pressure medium.

Tension springs 7 are located within the hollow spaces 20, and are attached to the end walls 3 and partitions 4.

Obviously, the springs 7 may be located outside of the bodies 5, if desired.

The springs 7 are used to pull the partitions 4 toward the members 3, as indicated in Figure 1.

The stretchable bodies 5 are enclosed by guides 9, consisting of inter-engaging, telescoping sections 19 of varying diameter. The innermost sections 19 are attached to the partitions 4, while the outermost sections are attached to the members 3. The sections 19 are slidable one upon the other so that they may be located in the extended position shown on the left side of Figure 1, or in the collapsed position shown on the right side of Figure 1.

The device is operated as follows:

Water is allowed to enter the container 10 and to fill one half of it. A water-softening and detergent composition is dissolved in this water. Then it is heated to the desired washing temperature.

The wash is inserted into the interior of the drum 12 through any suitable openings not shown in the drawings, whereupon it is washed and rinsed in the usual manner by rotating the drum 12, the interior of which communicates with the washing-fluid in the container 10 by the perforations in the cylindrical wall. At that time the partitions 4 are in their withdrawn position, as indicated on the right side of Figure 1.

Upon completion of the washing operation, and while the drum 12 is still running, the rinsing water is removed from the container 10.

In accordance with the present invention wa-

ter is removed from the wash by shifting inwardly the end partitions 4. This is accomplished by allowing water, which may be taken directly from the water pipes, or some other pressure medium, to flow through the conduits 6 into the hollow spaces 20. The pressure of the water will expand the bodies 5 and will press the end partitions 4 inwardly until they are moved into the position shown in Figure 1, namely, until they are moved close to the center of the drum 12. Since the drum 12 continues its rotation the wash is substantially uniformly distributed between the two end partitions 4. With increased pressure more and more water is pressed out of the wash. Upon completion of this operation the connection of the pipes 6 with the source of the pressure medium is interrupted and the hollow spaces 20 are connected by the pipes 6 and any suitable devices, not shown in the drawings, with any space or room, not under pressure. Then the springs 7 will move the end partitions 4 back to their initial positions, which are indicated on the righthand side of Figure 1, whereby a part of the water leaves the hollow spaces 20 through the pipes 6. The wash 25 can then be removed from the machine in the usual manner.

The operation of the machine is enhanced by a suitable construction of the parts thereof. For example, the inner surface of the movable partitions 4 are preferably quite smooth and, if necessary, polished so that the wash, in the course of the compression, will slide along these walls and thus can be uniformly distributed between them.

If available water pressure is not sufficient to compress the wash then the required water pressure can be produced by a pump which can be operated manually or by an electro-motor. It is apparent that the above example has been given by way of illustration, and that many changes can be made therein within the scope of the present invention. By way of example, the guide rails 8 which prevent a rotation of the longitudinally movable walls in relation to the immovable end walls 3, and which are necessary for washing machines the direction of rotation of which is periodically reversed, may be eliminated in the case of washing machines wherein the drum 12 rotates in one direction.

When the stretchable bodies 5 are sufficiently strong mechanically, or when they fill out the entire interior of the casing, it is possible to eliminate the guide members 9.

As already stated, the springs 7 may be located outside the hollow bodies 5, namely, they may be placed close to the edges of the end walls between the guides.

Washing machines of smaller size can be provided with only one movable end partition 4.

60

The described washing machines have considerable advantages in comparison with prior art devices. These machines can be constructed in every size, for household use as well as for large installations. The possibility of washing the clothes and removing water from them in a single device constitutes a considerable saving in work, time and space. The various operational steps which heretofore took place between the introduction of the wash into the washing fluid and the drying thereof are reduced to a single operation which requires very little supervision, particularly when the entire operation of the machine is regulated automatically. The wash will not be damaged by the pressure since it is not subjected to any twists or turns.

An advantage of the described machine, as compared to centrifuges, is that the machine, as constructed in accordance with the present invention, is able to attain pressure which can be achieved only with centrifuges capable of a high number of revolutions, requiring very firm and powerful installation and, thus capable of use only for large works.

If soap-carrying liquid is pressed out of the wash at the end of the main washing operation, a considerably smaller amount of water is required for the rinsing. This is particularly advantageous in localities having hard water.

What is claimed is:

A washing machine comprising a stationary casing, the casing having end walls, a drum rotatably mounted in the casing, the drum having at least one partition axially movable within the drum, resilient means for maintaining the movable partition adjacent the corresponding end wall of the casing, an elastic bellows surrounding the resilient means, and a conduit disposed through the stationary end wall for introducing the fluid pressure into the bellows and intermediate the movable partition and corresponding stationary end wall.

FRIEDRICH EBERLEIN.
